UNITED STATES PATENT OFFICE

WALTER H. COTTON, OF CHICAGO, ILLINOIS, ASSIGNOR TO UNION DRAFT GEAR COMPANY, OF CHICAGO, ILLINOIS, A CORPORATION OF DELAWARE.

DRAFT GEAR

Application filed September 22, 1923. Serial No. 664,141.

The invention relates to draft gears or shock absorbing devices for railway cars, and is of the so-called friction type in which the shocks incident to the pulling or buffing actions are largely absorbed by the friction between relatively movable parts. More specifically, the invention relates to that type of friction gears which include relatively movable intercalating plates with wedging means 10 for squeezing them together.

The principal object of the invention is to secure high efficiency. Other objects and advantages will be apparent in connection with the description, manner of installing, and 15 mode of operation of the improved gear.

The invention consists in a structure, a preferred embodiment of which is herein-after described and is shown in the accompanying drawings, in which

20 Fig. 1 is a detail plan view of the underframing of a car and of the improved gear, the latter being mainly, but not entirely, shown in central section;

25 Fig. 2 is a central vertical longitudinal section through the gear, and showing in elevation a detail of the coupler and a part of the underframing of the car;

Fig. 3 is a sectional view of the gear on the line 3—3 of Fig. 1;

30 Fig. 4 is a view similar to Fig. 1, the gear being shown fully compressed by a buffing action;

Figs. 5, 6 and 7 are views in perspective of 35 various wedging elements used in the gear; and

Fig. 8 is a detail of a spring seat used in the gear, and of the part to which it is anchored.

In the drawings there are shown portions 40 of a pair of center or draft sills 10, 10, to each of which there is attached a suitable draft lug 11, 11, and a buffing lug 12, 12. The butt of the coupler is shown at 13, and its extension or yoke element at 14. This yoke 45 is shown as in the common form of a loop for inclosing the gear.

Follower plates 15, 16, inclosed within the yoke 14, cooperate, respectively, with the draft and buffing lugs. A pair of box-like casings 17, 18, are housed within the yoke, 50

one being adjacent to each of the follower plates but normally spaced therefrom. Each of these casings is provided with an end wall adapted to be engaged by the adjacent follower plate, and with top, bottom and side 55 walls. The length of these casings is such that their inner ends come into contact to limit the compressive movement of the gear and prevent injury of its springs.

Slots, as 19, are formed longitudinally in 60 the side walls of each of the casings, and through the slots of each casing, and through suitable slots, as shown at 20, in the sills 10, extend bars 21, 22, between the end portions of which there react helical springs 23, 24. 65 Preferably, as shown, these spring elements each comprises a pair of nested springs. A suitable seat, as 25, 26, is applied to each end of each spring and bears directly against the bar with which it is associated, and to 70 which bar it is secured by a pin or bolt, as 27, in order to prevent its lateral displacement. By associating the spring elements with the end portions of the transverse bars they are located outside of the car sills, and consequently leave the entire cross-section of the 75 yoke-inclosed portion of the gear available for the friction and wedging elements.

Two groups of relatively movable intercalating plates are housed within the casings 80 17, 18, on opposite sides of the axis of the gear, these groups being generally designated by the numerals 28, 29. Each group of plates is located adjacent to the corresponding side wall of the casing 17, 18, and between the two groups are interposed the 85 wedging elements.

Each group of plates comprises two sets, as 30, 31, the one set normally extending from, or approximately from, the end wall 90 of the casing 17, and the other set from, or approximately from, the end wall of the casing 18. The length of these plates is preferably such that in the normal position of the gear they are slightly out of contact with the end wall of the casing to which they are adjacent, and will not come into contact with the end wall of the other casing when the gear is fully compressed. The plates are slotted, as shown at 32, 32, in what may be 100

called their head ends, to receive the bars 21, 22, the slots being somewhat longer than the width of the bars to permit some movement of the latter before the plates are set in motion. At their farther ends they are recessed, as indicated at 33, to permit them to have free movement relatively to the other bar.

Seated against the inner plate of each of the groups 28, 29, are two pairs of opposed wedging shoes 34, 35, and 36, 37. These shoes are identical in form, one of them being shown, removed from the gear, in Fig. 6. Each of these shoes comprises a flat base plate, for engagement with the inner friction plate, and instanding wedge members 38, 39, the front and rear faces of which are inclined to the axis of the gear in opposite directions, as shown at 40, 41. Each of these plates overlaps one of the bars 21, 22, and is slotted, as shown at 42, to receive the same.

Interposed between the outer wedging faces 40 of each pair of the shoes and the adjacent follower plate 15, 16, is a wedge-block 43, one of which is shown in Fig. 7 separated from the gear, the end wall of the adjacent casing 17 or 18 being apertured to accommodate it and to allow free relative movement of the casing and block.

Cooperating with the inner faces 41 of each pair of the shoes is a wedge-block 44, one of which is shown in Fig. 5 removed from the gear. Each of these blocks is provided with a shank 45, slotted, as shown at 46, to receive the adjacent bar 21 or 22; the length of the slot being somewhat greater than the width of the bar for convenience in assembling. The inner end of each of the wedge-blocks 43 is slotted, as shown at 47, to loosely receive the stem 45 of the adjacent block 44.

Normally the parts occupy the relative positions as shown in Fig. 1; the follower plates 15, 16, being in engagement, respectively, with the draft lugs 11 and buffing lugs 12; the casings 17, 18, are each spaced a short distance from the adjacent follower plate, the outer end of each of the slots 19 engaging the bar 21 or 22; the ends of each set of the two groups of friction plates are spaced a short distance from the end wall of one of the casings 17, 18; the wedge-blocks 43, 43, are in bearing each upon one of the follower plates and the outer wedging faces 40 of the pair of friction shoes with which it cooperates; each of the wedging blocks 44 is in engagement with the inner faces 41 of the wedging shoes; and the bars 21, 22, are spaced from the adjacent ends of the slots 20 in the sills.

Upon the application of buffing stresses the follower 15 is moved backwardly, carrying with it the associated wedge element 43, which, acting upon the shoes 34, 35, tends to spread and advance them. This advance movement carries forward the element 44, with which this pair of shoes is associated, and with it

the bar 21, which moves away from the ends of the slots in the casing 17, putting the springs 23, 24, under compression and moving backwardly the bar 22. This bar carries with it the casing 18 and the rearward element 44, the latter moving backwardly and spreading the shoes 36, 37. When the follower plate 15 engages the casing 17, the latter is moved backwardly, carrying with it the plates 30. The plates 31 move backwardly into engagement with the end wall of the casing 18, and come to rest when this casing engages the follower 16, the plates 30 continuing to advance. The compressive movement may continue until the parts reach the position shown in Fig. 4. Upon relief of the pressure upon the plate 15 the gear is released under the action of the springs 23, 24, and by the cooperation of the several wedging elements, the inclination of the wedging faces to the axis of the gear being greater than the angle of repose.

In draft the action is the same as in buffing, except, of course, that the movement of the parts is in the opposite direction. The resistance of the gear to compressing forces gradually and continuously increases as these forces are applied. The form and arrangement of parts are such that a large number of friction plates may be employed, and the gear has very high capacity and great durability.

While a preferred form of construction is shown, various changes may be made within the scope of the invention. The spring seats 25 are shown as provided with apertured lugs 48, 49, for the accommodation of retaining bolts (not shown), which may be inserted and form convenient means for compressing the springs to facilitate the assembling of the gear.

I claim as my invention—

1. In a draft gear, in combination, a pair of opposed chambered casings, two groups of intercalating friction plates housed within the casings, two pairs of opposed shoes interposed between the two groups of plates each shoe having oppositely inclined wedging faces, a spreading wedge at each end of the gear engaging the outer wedging faces of each pair of shoes, a wedging element engaging the inner wedging faces of each pair of shoes, such last-named wedging elements each having a transversely apertured stem projecting toward the adjacent end of the gear, a pair of bars extending transversely through the casings and stems, and compression springs interposed between the end portions of the two bars.

2. In a draft gear, in combination, a casing having side walls, intercalating plates inclosed within the casing, wedging means for compressing the plates, a pair of bars extending transversely through the gear and engageable with the wedging means for hold-

ing the elements thereof in cooperative relation and with the plates for effecting their withdrawal on release, and springs reacting between the end portions of the bars.

3. The combination in a draft gear, of a pair of opposed chambered casings, two pairs of opposed friction shoes each having oppositely inclined wedging surfaces positioned within said casings, friction elements between said shoes and the sides of said casings, a spreading wedge at each end of the gear engaging the wedging faces of each pair of shoes for forcing the same against said elements, a wedging element engaging the inner wedging faces of each pair of shoes, such last-named wedging elements each having a transversely apertured stem projecting toward the adjacent end of the said gear, a pair of bars extending transversely through the casings and stems, and compression springs interposed between the end portions of the two bars.

4. A draft gear comprising a pair of followers, a group of relatively movable intercalated friction plates, means including plate engaging shoe members and shoe engaging wedge members at each end of the gear for forcing said plates laterally, means for limiting the lateral movement of said plates, means including resilient elements located wholly outwardly of said plates for resisting the inward movement of said wedge members, said means engaging one of said wedge members at each end of the gear for releasing said wedge members upon the initial release movement of said gear and for returning said plates to inoperative position during the final release movement of said gear, one of said wedge members at each end of the gear having its wedge faces forming an acute angle and converging outwardly toward the end of the gear.

5. In a draft gear, a plurality of intercalated friction plates, retracting members to which said plates are connected, resilient means between said members, friction shoes in engagement with said plates, lateral pressure creating means engaging said shoes for forcing the same laterally into frictional contact with said plates, said means including wedging elements connected to said members and tapered toward the adjacent ends of said gear respectively, and means for resisting the lateral pressure of said plates.

6. In a draft gear, a plurality of intercalated friction plates, means including friction shoes, a bar, and a wedge member at each end of the gear for creating lateral pressure on said plates when said gear is compressed, said wedge members being connected to said bars and having their backs turned toward each other, means for resisting the lateral pressure of said plates, and means for resisting the longitudinal inward movement of said wedges upon the compres-

sion of the gear and for restoring the parts to normal position after compression.

7. In a draft gear, two sets of intercalated friction plates, a retracting bar connected with each set of plates, spring means for resisting the movement of said bars toward each other, friction shoes in frictional contact with said plates at the ends thereof, wedging mechanism operated by the compression of said gear for forcing said shoes into frictional contact with said plates, and means for resisting the lateral pressure of said shoes, said mechanism including a wedge member engaging each bar at each end of the gear and having its wedging faces forming an acute angle located between said bars.
